THERAPEUTIC COMPOSITION CONTAINING
TRIETHYLENE MELAMINE

Moses L. Crossley, Plainfield, N. J., assignor to
American Cyanamid Company, New York,
N. Y., a corporation of Maine

No Drawing. Application March 13, 1951,
Serial No. 215,379

5 Claims. (Cl. 167—65)

1

This invention relates to compositions and methods for the treatment of malignant growths; particularly lymphomas, (tumors of lymphoid tissue) and leukemias in man and animals.

In the medical field there has existed a need for a composition which will differentially cause a destructive action on tumor cells while at the same time having comparatively little or no effect on normal cells. In the past, the nitrogen mustards such as N,N-bis(beta-chloroethyl)-methylamine have been used in the treatment of lymphomas and certain leukemias. Although effective, N,N-bis(beta-chloroethyl)methylamine has not been very satisfactory because of undesirable and severe side effects.

I have now found that triethylene melamine is effective in causing clinical remission and remission of the blood in lymphomas and in certain leukemias. While triethylene melamine has some of the pharmacological actions of nitrogen mustard, it does not cause the severe side effects. For example, nitrogen mustard produces in patients, acute gastrointestinal upsets and psychic disturbances but these side reactions are not produced by triethylene melamine when used in proper therapeutic dosage. Furthermore, nitrogen mustard must be administered intravenously whereas triethylene melamine is effective when administered orally as a tablet, pill or capsule. It may also be administered parenterally, if desired, with the same diminution in side effects. Triethylene melamine affects adversely a greater number of malignant growths than does nitrogen mustard.

It has also been found that triethylene melamine on a weight basis is about one-half as toxic as nitrogen mustard and that it is about twice as active. Triethylene melamine is better tolerated by the patient than nitrogen mustard since it possesses a greater spread between the minimum effective dosage and the maximum tolerated dosage i. e. its effective therapeutic range is much greater.

The optimum single intravenous dosage in humans appears about 2 to 3 mg. administered twice a week for a course of two weeks; the optimum therapeutic dosage then being about 8-12 mg. for a two week course of treatment though dosages as low as 5 mg. and as high as 20 mg. for the two week course have been used with good therapeutic effect. The dosage will vary considerably with the age of the patient, the condition of the patient and the progression of his disease. Therefore, single therapeutic doses may be advisable as low as 0.5 mg. and as high as 6 mg.

and the frequency of administration may vary widely. In smaller animals, such as the dog, the single therapeutic dosage will be comparably lower for example, a single therapeutic dosage may be advisable as low as 0.01 mg.

The optimum single oral dosage in humans appears about 5 mg. administered twice a week for a course of four weeks, the optimum therapeutic dosage then being about 40 mg. for a four weeks course though doses as low as 15 mg. and as high as 100 mg. for a four weeks course have been used with good therapeutic effects. The oral dosage will vary considerably with the age of the patient, the condition of the patient and the progression of his disease. Therefore, single oral doses may be advisable as low as 1 mg. and as high as 10 mg. and the frequency of administration may vary widely. In smaller animals, such as the dog, the single therapeutic oral dosage will be comparably lower, for example, a single oral dosage may be advisable as low as 0.01 mg.

The compound triethylene melamine, known chemically as 2,4,6-tris(ethylenimino)-s-triazine was first described by Pingree and Dahlen on pp. 53, "Textile Finishing Treatments," PB-1576, published by the Office of Technical Services, Department of Commerce, Washington, D. C. It was developed for the control of shrinkage of cellulose materials and had no known therapeutic properties. An improved method for its preparation is described in U. S. P. 2,520,619.

The compound triethylene melamine when used in the treatment of animals such as the dog, having lymphomas, showed a marked ability to cause the remission of such lymphomas. When used clinically in the therapy of cancers of the blood forming tissues in man it was effective in bringing about the remission of Hodgkin's disease for periods of time that vary with different individuals. The compound was also found useful in producing clinical remission in certain leukemias for periods of time that vary with different individuals.

The compound of the invention may be dispensed in any of the usual dosage unit forms of pharmaceutical preparations. For example, tablets, capsules, pills, solutions, as a powder or in any other desirable form in the therapeutic quantities hereinbefore given. It may be in a dosage-unit form for a single daily therapeutic dose or in smaller units for multiple doses or in larger units for division into single doses. Obviously in addition to the therapeutic product there may be present excipients, binders, fillers and other therapeutically inert ingredients necessary in

the pharmaceutical preparation. For parenteral administration it may be dissolved in a liquid medium as for example in physiological saline solution or in a vegetable oil. For example, we may mix 5 to 10 mg. of triethylene melamine with 95 to 99 mg. of sterile salt in the dry state in a vial or ampule and the mixture may be dissolved with the appropriate amount of sterile water to produce a freshly prepared solution for parenteral use as needed.

For oral administration, it may be compressed without or with other ingredients into tablets or pills or it may be filled into capsules. A compressed, scored 5 mg. tablet is found convenient for administration.

I claim:

1. A therapeutic composition for the treatment of leukemias and lymphomas in dosage-unit form comprising 0.01 mg. to 10 mg. of triethylene melamine per dosage unit and a solid pharmaceutical carrier.

2. A therapeutic composition for oral administration in the treatment of leukemias and lymphomas in dosage-unit form comprising from 0.01 mg. to 10 mg. of triethylene melamine per dosage unit and a solid pharmaceutical carrier.

3. A therapeutic composition for intravenous administration in the treatment of leukemias and lymphomas in dosage-unit form comprising from 0.01 mg. to about 6 mg. of triethylene melamine 30

for each dosage unit and a sterile parenteral water diluent containing inorganic salts.

4. A therapeutic composition for the treatment of leukemias and lymphomas in dosage unit form comprising from 0.01 mg. to 10 mg. of triethylene melamine and a solid pharmaceutical carrier, said composition being in tablet dosage unit form.

5. A therapeutic composition in dosage unit form for the treatment of leukemias and lymphomas comprising from about 0.01 mg. to 10 mg. of triethylene melamine and a significant amount of a pharmaceutical carrier.

MOSES L. CROSSLEY.
